SKEIN HOLDER

Henry J. Maxfield, Westerville, Ohio

Application August 10, 1950, Serial No. 178,621

4 Claims. (Cl. 242—127)

1

My invention relates to a skein holder. It has to do, more particularly, with a holder for a skein of yarn or similar material to facilitate use of the material without first winding it into balls or to facilitate winding of the material into balls.

As is well known, it is customary to wind a skein of yarn into a ball before using it for knitting, et cetera. Usually, one person must hold the skein while another person unwinds it and rolls it into a ball.

It is the main object of this invention to provide a holder for a skein of yarn which will hold it in such a manner as to prevent tangling thereof while it is being unwound from the skein and is used directly or is wound into a ball.

Another object of my invention is to provide a skein holder upon which the skein can be mounted quickly and easily.

Another object of my invention is to provide a skein holder which can be adjusted quickly to receive skeins of various lengths.

Still another object of my invention is to provide a skein holder which will keep the skein taut after it is disposed thereon.

Various other objects will be apparent.

According to my invention, my device consists of a mandrel which is rotatably mounted on a suitable stand. This mandrel carries pins adjacent its opposite ends which extend radially therefrom and upon which the ends of the skein may be looped after it is wound helically on the mandrel. The mandrel is so constructed that the pins can be adjusted angularly so that the device can receive skeins of various lengths. Furthermore, means is associated with the pins for resiliently moving them away from each other to keep the yarn taut.

The preferred embodiment of my invention is illustrated in the accompanying drawing wherein similar characters of reference designate corresponding parts and wherein:

Figure 1 is a side perspective view of my skein holder.

Figure 2 is a side elevational view, partly broken away, of the holder.

Figure 3 is a transverse sectional view taken substantially along line 3—3 of Figure 2.

Figure 4 is an end perspective view of the holder.

Figure 5 is a schematic view illustrating how the holder is used.

With reference to the drawing, I have illustrated my holder as comprising a stand 10 which includes the upstanding arms 11 that are provided with bearings 12 on their upper ends. The stand 10 carries the cylindrical member 13 upon which

2

the skein is to be disposed. This cylindrical member 13 is supported by means of a shaft 14 which extends into the bearings 12 and is rotatably disposed therein.

The structure of the member 13 is illustrated best in Figures 2 and 3. It comprises a main section 15 which has a smaller end section 16 rotatably connected thereto. The rotatable connection includes a telescoping joint 17 and friction springs 18. It will be noted that the outer surfaces of the sections 15 and 16 are flush and that the section 16 carries the springs 18 on its interior, these springs extending over and engaging the inner surface of the section 15. This arrangement permits relative rotation of the sections 15 and 16 and will keep such sections in any rotatively adjusted relationship until positively changed. Each of the sections 15 and 16 has a skein-retaining finger 19 associated therewith. These fingers are rotatably mounted by sleeve portions 20, at their inner ends, on the shaft 14. The sleeve portions 20 are axially movable on the shaft 14. One of the pins 19 extends radially outwardly through a helical slot 21 in the section 15 adjacent its outer end. The other finger 19 extends through a similar helical slot 22 in the section 16 adjacent its outer end. The slots 21 and 22 are substantially parallel and instead of being helical may merely be angular. It will be noted that each pin 19 is provided with an enlarged knob or head 23 on its outer end. As shown in Figure 3, springs 24 are connected to the inner ends of the pins 19 and are anchored to the corresponding sections of member 15 which carry the pins. These springs are so arranged that they tend to swing the pins 19 in opposite directions in the slots 21 and 22.

In the use of this device, the section 15 and the section 16 are rotated relatively to position the pins 19 at different angular positions around the axis of the shaft 14. A skein S is mounted on the member 13 and is wrapped around it helically with its ends looped over the angularly spaced pins 19. The relative rotation between the sections 15 and 16, which is maintained by friction springs 18, will be used to cause the skein to be tightened on the cylindrical member 13. This rotation will bring the pins 19 into the ends of the slots 21 and 22 where they will approach each other as far as possible. The springs 24, on the other hand, will function to tend to move the pins 19 into the opposite ends of the slots or in other words, to move the pins 19 farther apart. This will act as resilient means for keeping the yarn of the skein taut.

As shown in Figure 5, the yarn may be used

directly from the holder. A pull on the yarn will merely oscillate the member 13 back and forth, as indicated diagrammatically in Figures 3 and 4, the yarn being unwound from the skein without danger of tangling. However, as previously indicated, if desired, the yarn can be rolled into balls.

It will be apparent from the above description that I have provided a simple device for holding a skein of yarn to permit unwinding thereof without tangling. The device is adjustable for different size skeins and includes automatic means for keeping the yarn taut. The device is extremely simple and can be manufactured at low cost.

Various other advantages will be apparent.

Having thus described my invention, what I claim is:

1. A skein holder comprising a cylindrical mandrel upon which the skein is adapted to be disposed helically, a stand upon which said mandrel is mounted for rotation, pins projecting radially from said mandrel adjacent opposite ends thereof, means for adjusting said pins to angularly spaced positions and maintaining them in such positions, means for supporting said pins for movement towards and away from each other, and resilient means tending to move said pins away from each other.

2. A skein holder comprising a cylindrical mandrel upon which the skein is adapted to be disposed helically, a stand for supporting said mandrel, said mandrel being provided with a shaft extending axially therethrough which is rotatably mounted in bearings carried by said

stand, pins mounted on said shaft for swinging movement about the axis of said shaft and for movement axially of the shaft, said pins extending radially outwardly through slots disposed adjacent the ends of said mandrel, said mandrel being composed of two relatively rotatable sections in which the slots are separately formed, said slots extending helically substantially parallel to each other.

3. A skein holder according to claim 2 wherein springs are connected to said pins for swinging them about the axis of said shaft to move them into the opposite ends of said slots, the ends being the ones spaced farthest apart.

4. A skein holder comprising a cylindrical mandrel upon which the skein is adapted to be disposed helically, means for supporting said mandrel for rotation, pins projecting radially from said mandrel adjacent opposite ends thereof upon which the helically disposed skein is looped, means for supporting said pins for relative angular movement around the mandrel, and resilient means tending to move said pins angularly relatively around the mandrel to maintain the skein taut.

HENRY J. MAXFIELD.
